UNITED STATES PATENT OFFICE

2,674,376

FILTERING OR SCREENING APPARATUS

Charles J. Swan, Toledo, Ohio, assignor to The Standard Oil Company, Cleveland, Ohio, a corporation of Ohio

Application November 13, 1950, Serial No. 195,160

4 Claims. (Cl. 210—155)

1

When it is desired to separate solid particles from a downwardly flowing liquid mass in a container, as for instance in a petroleum refining evaporator tower which receives more or less return stream from a coking zone, it has been customary to rely on a screen filter at the bottom outlet. Such an arrangement blocks up after a short time and it is necessary to then shut down, and workers must enter and clean the blocked filtered surface. The frequent interruptions of operation add disproportionately to costs, in addition to the excess labor. I have now found that this quick blocking trouble may be obviated by an arrangement according to the present invention. Operating and maintenance costs may thus be importantly lowered. Other objects and advantages will appear from the following description.

To the accomplishment of the foregoing and related ends, the invention then, comprises the features hereinafter fully described and particularly pointed out in the claims, the following description and the annexed drawing setting forth in detail certain illustrative embodiments of the invention, these being indicative, however, of but a few of the various ways in which the principle of the invention may be employed.

In said annexed drawing:

Fig. 1 is a side elevational view of a filter embodying the invention, the container being shown in section; and

Fig. 2 is a plan view of the filter or screen.

The construction in the present invention provides greater increased surface area for a submerged filter, and so placed as to occasion eddy currents to favor sweeping and cleaning instead of allowing settling on the surface. The solid particles can then settle below. In general, the filter is of T-shape with a vertical stem section set over the container outlet, and a horizontal section on top of the vertical section, each portion being of cross-section obviating flat particle-collecting areas; in other words being of rounded cross-section. Thus in a tower container 2 a T-shaped filter or screen involves a vertical cylindrical section 3 of suitable strong wire mesh or less desirably in some cases perforated sheet metal, and this is topped by horizontal cylindrical section 4 with ends also of screen. The vertical section is secured to the bottom of the tower or container by suitable means, over the outlet 5, such as by brackets 6 secured to the floor and to the screen. The top of the vertical section 3 is shaped to fit with the horizontal cylindrical section 4, the space with-

2

in forming one complete exit chamber for the liquid. The course of the liquid flow is downwardly, the feed to the tower or container being above the filter. Inasmuch as the filter is relatively large, it is advisable to have the sections disassemblable, and the horizontal section may be removably secured to the top of the vertical section by suitable means such as lugs 7 on the horizontal section which may be held by bolts 8 to the lugs 9 on the vertical section, and over the top of the horizontal section is a band 10 having its ends secured by bolts 11 to lugs 12 on the vertical section. For additional support and stability, supports 14 may extend between the floor 10 and the horizontal section 4 at each end and be bolted to lugs 15 on the horizontal section. Conveniently, one or two manholes 21 in the side wall of the container adjacent, affords access whereby the screen sections may be introduced and be set up in assembly, and when occasion requires may be disassembled and removed. It will be understood that the manholes are of size sufficient for entry of workers and to permit removal of accumulated settling from the bottom. The manhole cover or head 22 may be held in position by bolts, as well known.

In operation, the liquid mass is fed into the container above, cleaned liquid, for instance heavy petroleum being drawn off through the bottom outlet 5. And by reason of the shape and arrangement of the filter the liquid currents which are occasioned sweep the sides, hindering sticking of solid particles, and the particles then settle at the bottom. When the settling have accumulated to a height which requires cleaning out of the accumulation, the necessity for this being indicated by the change in pressure gauge reading on the pump lines, the intake may be shut off, and with draining down below the manhole the heads may be removed, and workers can enter and clean out the settling accumulation.

Other modes of applying the principle of the invention may be employed, change being made as regards the details described, provided the features stated in any of the following claims, or the equivalent of such, be employed.

I therefore particularly point out and distinctly claim as my invention:

1. In apparatus of the character described, a closed container, a manhole in the side, and screening means of overall greater size than the manhole and insertible in sections to be put together inside and presenting a screening surface extended transverse to the downward current

flow, including a hollow vertical screen section and a hollow horizontal screen section removably secured to the top thereof in communication with it, said vertical section having an outlet below through the bottom of the container.

2. In apparatus of the character described, a liquid container, a closable manhole in the side thereof, an outlet at the bottom of the container, and screening means of overall greater size than the manhole and insertible in sections to be put together inside and presenting a screening surface for said outlet extended transverse to the downward current flow, including a filter having a hollow cylindrical vertical section secured to the bottom of the container and having its outlet over said container bottom outlet, a hollow cylindrical horizontal section having screen ends and fitting the top of said vertical section in communication therewith, and means for removably securing the horizontal section to the vertical section.

3. In apparatus of the character described, a petroleum-evaporator tower having a closable manhole in the side and having a bottom outlet, and screening means of overall greater size than the manhole and insertible in sections to be put together inside and presenting a screening surface for said outlet extended transverse to the downward current flow, including a hollow vertical screen section secured to the tower floor with outlet over said bottom outlet, and a hollow horizontal screen section having screen ends and secured to the top of the vertical section in communication therewith, lugs on the respective sections for bolts fastening the sections together, and a clamp-band across the top of said horizontal section and having its ends bolted to lugs on the vertical section.

4. In apparatus of the character described, a

liquid container, a closable manhole in the side thereof, an outlet at the bottom of the container, and screening means of overall greater size than the manhole and insertible in sections to be put together inside and presenting a screening surface for said outlet extended transverse to the downward current flow, including a hollow cylindrical vertical screen section with one end secured to the bottom of the container with outlet over the said container bottom outlet, a hollow cylindrical horizontal screen section having screen ends and fitting the top of said vertical section in communication therewith, lugs on the respective sections for bolts fastening the sections together, a clamp-band across the top of said horizontal section and having its ends bolted to lugs on the vertical section, and supports extending from the floor of the container to the respective end portions of the horizontal section.
